(57) **CLAIM**

The ornamental design for a glove for industrial operators, as shown and described.

DESCRIPTION

FIG. 1 is a perspective view of a glove for industrial operators, according to our new design;

FIG. 2 is a top plan view thereof;

FIG. 3 is a left elevation view thereof;

FIG. 4 is a right elevation view thereof;

FIG. 5 is a bottom plan view thereof;

FIG. 6 is a front elevation view thereof; and,

FIG. 7 is a rear elevation view thereof.

FIGS. 1-7 illustrate a left-handed glove design of the present invention. It is understood that the invention further includes a right-handed glove design, the views of which would be illustrated as mirror images of any, or all, of the views shown in FIGS. 1-7.

The ornamental design which is claimed is shown in solid lines in the drawings. The broken lines in the drawings form no part of the claimed design. Surfaces shown with line or stipple shading may or may not have a contrast of appearance with each other.
